United States Patent

Des. 237,681
Patented Nov. 18, 1975

237,681

ROOF INSULATION WASHER

Rudolph Ernst Knohl, Bartlett, and Robert Victor Enstrom, Oak Park, Ill., assignors to Illinois Tool Works Inc., Chicago, Ill.

Filed Nov. 19, 1973, Ser. No. 417,449

Term of patent 14 years

Int. Cl. D8—08

U.S. Cl. D8—274

FIG. 1 is a top view of the roof insulation washer.
FIG. 2 is a bottom view of the washer device.
FIG. 3 is a side elevational view of the washer device.
FIG. 4 is an enlarged diagonal cross-sectional view thereof taken along the lines 4—4 in FIG. 1.

We claim:

The ornamental design for a roof insulation washer, as shown.
